(57) **CLAIM**

The ornamental design for a tire, as shown and described.

DESCRIPTION

FIG. 1 is a perspective view of a tire showing the new design.

FIG. 2 is a front view thereof. The top, bottom, and rear views thereof each are identical to the front view.

FIG. 3 is a left side view thereof. The right side view thereof is identical to the left side view; and,

FIG. 4 is a detail view from upper 4-4 to lower 4-4 of FIG. 2.

The broken lines illustrate environmental subject matter only and form no part of the claimed design. The surface shading lines and stippling in the drawings depict the character or contour of the surfaces represented and themselves are not part of the claimed design. The dash-dot-dash line indicates a boundary of the design and is not itself part of the claimed design.
